COLOR TV PHASE COMPARATOR AND FM DETECTOR CIRCUITS UTILIZING VACUUM TUBE INTERMITTENTLY OPERATING IN SECONDARY EMISSION MODE

Donald R. Taylor, Jr., Philadelphia, Pa., assignor to Philco Corporation, Philadelphia, Pa., a corporation of Delaware

Filed July 11, 1963, Ser. No. 294,284
5 Claims. (Cl. 178—5.4)

This invention relates to a novel and improved phase discriminator circuit and more particularly to a phase discriminator whose principle of operation includes a vacuum tube current reversal or secondary emission effect of the type first discussed in my previous application, Serial No. 190,114, filed April 25, 1962, entitled Synchronizing Signal Separator Making Use of Forward and Reverse Space Charge Currents, now Patent 3,192,314, granted June 29, 1965 and assigned to the present assignee.

A phase detector or discriminator is a circuit which functions to produce a D.C. output signal whose polarity and magnitude are respectively indicative of the sign and magnitude of the phase difference between plural A.C. input signals. Such discriminators have taken diversified forms and find application in a variety of systems, including control circuitry, television, etc.

The current reversal or secondary emission effect above referred to relates to the principle of operation of multi-grid vacuum tubes wherein a reverse or secondary emission current will flow if the conventional suppressor grid is made more positive than the conventional plate when certain other conditions are satisfied. More particularly, a vacuum tube having a control grid, one or more intermediate grids, a last grid, and a plate may be operated in alternate secondary emission and normal conduction modes if the tube is biased into conduction at the first or control grid, a B+ potential is applied to one of the intermediate grids, and respective signals are applied to the last grid and the plate. When the plate is more positive than the last grid, conventional plate current will flow. When the last grid is the more positive, reverse or secondary emission current will flow in the plate. The presence and magnitude of the normal and reverse plate currents may be respectively controlled by the presence and magnitude of the signal at the first grid.

If the signals on the first grid, last grid and plate are arranged so that the normal and reverse plate currents average to zero at a reference phase relationship between two of the signals, then at other phase relationships an unbalanced alternating current, indicative of the sign and magnitude of the phase relationship, will flow. If the signal-frequency components are filtered from this net plate current, a bipolar phase-indicative signal may be obtained.

In addition to a basic phase discriminator utilizing this secondary emission effect, several exemplary ramifications thereof will be described. A color TV chroma reference discriminator or combined burst keyer-chroma reference discriminator may be easily and simply provided utilizing the principles of the invention. Also a novel combined FM limiter-discriminator will be shown and discussed.

OBJECTS

Accordingly the objects of the present invention are:

- (1) To provide a novel and improved phase discriminator,
- (2) To provide a novel mode of operation of multi-grid vacuum tubes,
- (3) To provide new and improved chroma reference discriminator circuits, and
- (4) To provide a new FM limiter-discriminator circuit.

2

Other objects and advantages of the invention will become apparent from a consideration of the following description thereof and accompanying drawings.

SUMMARY

According to one embodiment of the present invention two A.C. signals are applied to the circuit of the invention for phase comparison and a third, phase-indicative, signal is obtained at the output of said circuit. One of the A.C. signals is utilized to turn on a multi-grid tube on positive half cycle intervals thereof. Two versions of the other of the A.C. signals are applied to the plate and last grid, respectively, of the tube at phase angles such that normal and secondary emission currents alternately flow in the plate circuit. These currents average to zero when the two original A.C. signals are in phase. The phase indicative signal is recovered, via a filter, from the alternating current in the plate of the tube.

FIG. 1a—PHASE DISCRIMINATOR

Description

The circuit depicted in FIG. 1a is a basic circuit of the invention which compares the signals generated by sources 10 and 12 to produce a voltage at output 14 whose polarity indicates whether the signal from source 12 (arbitrarily designated ϕB signal) leads or lags the signal from source 10 (arbitrarily designated ϕA signal), and whose magnitude indicates the degree of phase difference between the ϕA and ϕB signals.

The ϕA signal is retarded in phase by 45° in phase shifter 16 and is applied to grid #1 of pentode 18 via RC circuit 20. One cycle of the resultant signal appearing on the first grid of pentode 18 is depicted as waveform e_{g1} in FIG. 1b. The ϕA signal from source 10 (not shown) is substantially identical to signal e_{g1} , except that its phase position is 45° ahead of e_{g1} . RC circuit 20 is a familiar self-bias circuit which is arranged to bias pentode 18 so that only the positive portion of signal e_{g1} turns pentode 18 on. Other methods of biasing pentode 18 to secure a similar result, which are well known to the skilled artisan, may be used in lieu of RC circuit 20.

The ϕB signal is applied to grid #3 (the suppressor) of pentode 18 via 90° phase shifter 26 and capacitor 22, and to the plate of pentode 18 via capacitor 24. Although the suppressor and plate of pentode 18 do not perform their conventional functions in the circuit of FIG. 1a, these names will be retained and the signals present on these elements will be respectively designated e_s and e_p . One cycle of each of these signals is depicted in FIG. 1b on the same time scale as signal e_{g1} , but on a separate time axis. It may be noted that signal e_s is 45° behind e_{g1} , and signal e_p , which is identical to signal ϕB from source 12, is 45° ahead of signal e_{g1} .

Bias voltage source 28 is connected to grid #2 of pentode 18 via resistor 30. A bypass capacitor 32 is connected between grid #2 and ground. Grid #3 is connected to ground via resistor 34. The plate of pentode 18 is connected to output terminal 14 via filter 36.

Operation

When signals ϕA and ϕB are in phase, the signals e_p , e_s , and e_{gl} will have phases as represented by the curves in FIG. 1b. During part of the interval from time t_0 to time t_2 , when plate voltage e_p is more positive than grid #3 voltage e_s , normal plate current, represented by the positive portion of curve i_p , will flow. After e_s becomes greater than e_p at time t_2 , grid #3 will collect electrons from the plate and a reverse or secondary emission plate current, represented by the negative portion of curve i_p , will flow. The area under the positive portion of curve i_p should be equal to the area included within the negative portion so that no net plate current will flow when signals ϕA and ϕB are in phase. Filter 36 removes the signal frequency component of the signal appearing on the plate, leaving only the phase indicative component to be applied to output terminal 14. Since the ϕA and ϕB signals are in phase, waveform i_p has no D.C. component; thus no voltage will appear at terminal 14.

Due to inherent asymmetries in the system, a D.C. voltage may appear at terminal 14 when phase coincidence does exist. This can easily be remedied by decreasing or increasing the amplitude of one of the signal sources, or by increasing or decreasing the phase shift produced by one of the phase shifters. For instance, if at phase coincidence, a positive voltage appears at point 14, this indicates the positive portion of the current represented by waveform i_p is greater than the negative portion thereof. This can be remedied if one or more of the following be done: the alternating signal e_p supplied to the plate may be decreased in amplitude, the amplitude of the signal e_s may be increased, the signal e_p may be retarded more than 90° , or the signal may be retarded less than 45° .

Assuming that the circuit is properly adjusted, the operation when signal ϕA is not in phase with signal ϕB will now be described. Assume that signal ϕA leads signal ϕB . Waveform e_{gl} will be shifted to the left in relation to waveforms e_p and e_s as shown by the broken line e_{gl}' and the conducting or "on" intervals of tube 18 will be similarly advanced in time. The left or positive portion of waveform i_p will be increased while the negative portion thereof will be decreased as shown by the broken line i_p' ; thus a net positive D.C. voltage will appear at point 14. If signal ϕA lags ϕB , a negative D.C. voltage will appear at point 14. The magnitude of the D.C. voltage, whether positive or negative, will be proportional to the magnitude of phase difference between signals ϕA and ϕB .

In FIG. 1b, signal e_{gl} has been shown for purposes of illustration as equal in size to signals e_p and e_s ; however in practice e_{gl} , a grid signal, will normally be much smaller than the plate and suppressor signals. Moreover signals e_s and e_p have been shown as equal in amplitude, with signals e_s and e_p respectively 45° behind and 45° ahead of signal e_{gl} . It will be apparent to those skilled in the art that the invention is not limited to these specific interrelationships between signals e_{gl} , e_s , and e_p . Furthermore the signals are not limited to the sinusoidal shapes shown in the drawings; any shape repetitive waveform may be used in accordance with the invention. The only requirement necessary for operability is that the phase, amplitudes, and shapes of the signals applied to the tube be selected so that the forward (normal) and reverse (secondary emission) plate currents average to zero when the two input signals to be compared are in phase coincidence.

It is also seen in FIG. 1a that one of the 2 input signals (ϕB) is "split" into two versions which are applied to

the plate and suppressor, respectively. The signal which is "split," may be either one of the two input signals, i.e., it is immaterial whether the signal which is split is a standard phase signal or the signal of variable phase.

5 Furthermore it is immaterial to which two of the three tube elements (plate, suppressor, and grid #1) the two versions of the input signal which is "split" are applied, so long as the phases, amplitudes, and shapes of the applied signals are adjusted so that the normal and reverse plate currents average to zero when the two input signals are at phase coincidence.

10 Several exemplary modifications of the conditions existing in FIGS. 1a and b will now be discussed to illustrate the foregoing principles.

15 FIGS. 2a, b, c—PHASE DISCRIMINATOR MODIFICATIONS

FIG. 2a— e_{gl} in phase with e_s

20 In FIGS. 1a and b, signals e_p and e_s were illustrated as equally displaced in phase (by 45°) from signal e_{gl} . If signal e_s is arranged to be closer in phase than 45° from signal e_{gl} , a concomitant shift of signal e_p away from e_{gl} by more than 45° will still enable the normal and reverse plate currents to average to zero. This is depicted in FIG. 2a, where for purposes of simplification, signal e_s is illustrated as in phase with signal e_{gl} and signal e_p as 90° ahead of signal e_{gl} , although similar results will follow if signals e_s and e_p are made to respectively and 25 proportionally lead signal e_{gl} by anywhere from 0° to 45° and lag by anywhere from 45° to 90° . Plate current will flow under the phase conditions illustrated in the FIG. 2a substantially only from times t_0 to t_2 , since this interval is the only time that both signals e_{gl} and e_p are greater than cutoff and cathode potential, respectively, a condition essential for plate current flow. As shown, normal plate current will flow when signal e_p is greater than signal e_s , (times t_0 to t_1), and reverse or secondary emission current will flow when signal e_s is greater than signal 30 e_p (times t_1 to t_2).

35 The phase relationships depicted in FIG. 2a may be easily achieved for example, by applying input signal ϕA to grid #1, applying input signal ϕB to the suppressor, and applying a 90° delayed version of either signal ϕA or ϕB to the plate. It should be noted that in FIG. 2a as in FIG. 1b, signals e_p and e_s are again shown as having equal amplitudes for convenience.

FIG. 2b— e_{gl} in phase with e_p ; $e_p < e_s$; e_p leads e_s

40 50 If the signal e_p is brought closer to or into phase with signal e_{gl} , then signal e_s may be increased in amplitude in order to enable the normal and reverse plate currents to average to zero. In FIG. 2b, for purposes of simplification, signals e_{gl} and e_p are illustrated as in phase, and signal e_s as lagging by 45° . Many obvious ways of shifting the phase and altering the amplitude of the two input signals, ϕA and ϕB , to produce the conditions shown are available and will not be discussed. The normal and reverse plate currents will average to zero from times t_0 to 45 t_4 as shown.

FIG. 2c— e_{gl} in phase with e_p ; $e_s > e_p$; e_s leads e_p

55 65 In FIG. 2c the same amplitude and phase relationships as in FIG. 2b are maintained with the exception that signal e_s leads signals e_{gl} and e_p by 45° . Under these conditions the normal and reverse plate currents i_p can again be made to average to zero; it will be observed however, that the reverse plate current interval precedes the normal plate current interval in this embodiment.

70 75 Many other variations of the phase position and amplitude of the three signals, e_{gl} , e_s , and e_p which will allow current i_p to average to zero when the input signals are in phase coincidence will be apparent to those skilled in the art and no further examples will be discussed. Accord-

ingly the scope of invention is not limited to the foregoing examples.

CHROMA REFERENCE DISCRIMINATOR APPLICATION

Since the apparatus of the invention provides a phase discriminator in a simple fashion substantially within a single tube structure, it may advantageously be used as a color TV chroma reference discriminator, wherein the phase of the incoming reference bursts is intermittently compared with the phase of the signal from a reference oscillator to produce an automatic phase control voltage which maintains the phase of the reference oscillator signal identical to that of the incoming bursts. Referring back to FIG. 1a, if source 10 represents the source of incoming bursts and source 12 the reference oscillator, the desired APC voltage will be supplied to point 14. The three signals, e_{gl} , e_s , and e_p , may be derived in any manner from the incoming burst and reference oscillator signal as afore-discussed; the phases and amplitudes of the signals e_{gl} , e_s , and e_p must, of course, be arranged so that no net plate current flows when the bursts and the reference oscillator have like phase. The signal e_{gl} which is applied to grid #1 should be derived from the bursts so that the pentode 18 will be conducting only when bursts are present; otherwise an APC voltage might be produced when no bursts are being compared with the reference oscillator signal.

FIG. 3—CHROMA REFERENCE DISCRIMINATOR BURST KEYER

The circuit of FIG. 3 illustrates a combined chroma reference discriminator/burst-keyer utilizing the phase discriminator of FIG. 1a. Because the phase discriminator of the invention is inherently simple in requiring only three tube elements, an additional function can be performed in the same tube structure if a multi-grid tube is utilized. In FIG. 3 the complete chroma signal 38 is applied to the control grid of heptode 18'. To the third grid is supplied a conventional burst keying signal 40 in phase with the bursts in signal 38. Heptode 18' can conduct only when burst keying signal 40 is present; thus a time selection function will be performed on signal 38 so that the space current of tube 18 will conform only to the bursts in signal 38. Signals e_p and e_s , one or both of which are derived from a local oscillator (L.O.), are applied to the plate and suppressor at such phase and amplitude that the plate current will average to zero when the bursts and the local oscillator signal are in phase. When the bursts and the L.O. signal are out of phase a D.C. signal will appear at point 14 which may be employed as an automatic phase control (APC) voltage to correct the phase of the L.O. signal in conventional fashion.

FIG. 4—LIMITER/FM DISCRIMINATOR

Description

The circuit of FIG. 4a shows a single tube combined IF limiter amplifier/FM discriminator utilizing the phase discriminator of the invention. Any FM-modulated signal 40 may be applied at input 42, and the modulation signal, which is usually of audio frequency, is obtained at output 44.

The circuit utilizes a heptode having 5 grids, g_1 to g_5 . Any FM-modulated carrier, represented in FIG. 4a as signal 40, is applied to input 42, the primary of tuned transformer circuit 48. The secondary of tuned transformer circuit 48 is coupled to grid #1 of tube 46 via RC bias circuit 50. A fixed bias supply voltage 52 is coupled, via resistor 53, to grid #2. Grid #2 function as a screen grid. Resistor 53 is bypassed by capacitor 54. Grid #3, which functions as a suppressor, is grounded, and grid #4, which functions as a plate, is coupled to one terminal of the tuned primary winding 56 of three winding transformer 58. The other terminal of the primary winding 56 is connected to bias source 52 via resistor 53.

Transformer 58 has primary, secondary, and tertiary windings, as indicated. The transformer may be similar to those constructed for normal 4.5 mc. discriminators or ratio detectors, and is shown, for example, on pp. 12-36 of the Radio Engineering Handbook by Henney (5th ed. 1959). One side of the tertiary winding is grounded (or returned to a bias potential) and the other is center-tapped to the secondary winding. The secondary winding, like the primary, is tuned with a shunt capacitor. One side of the secondary winding is coupled to the plate of tube 46 via capacitor 60, while the other side is connected to grid #5 of tube 46. Grid #5 (which usually functions as a suppressor), and the plate, correspond in functional application to the last grid and plate of tubes 18 and 18' in FIGS. 1a and 3, respectively.

The plate of heptode 46 is connected to one side of a conventional FM deemphasis and filter network 62. The other side of deemphasis network 62 is connected to output terminal 44.

Operation

The operation of the circuit of FIG. 4a may be most easily understood if it is first noted that three functions are performed therein: the cathode and first four grids of tube 46 function as a limiting amplifier; the transformer circuitry functions as a frequency-to-phase converter; and the fifth grid and plate circuit function as a phase comparator. These three functions will be separately discussed.

(1) LIMITING AMPLIFIER

The cathode and first four grids of heptode 46 are analogous to an ordinary pentode, with grid #4 acting as a plate. IF carrier signal 40 is applied to tuned transformer circuit 48 at a level such that sufficient limiting will occur to eliminate noise pulses therefrom in conventional manner; the amplified and limited IF carrier signal will appear across tuned primary circuit 56 of transformer 58.

(2) TRANSFORMER FREQUENCY-TO-PHASE CONVERTER

Reference will be made to the vector diagrams of the transformer waveforms in FIG. 4b to explain the principle of operation of three winding transformer 58.

It is known that the voltage across the secondary winding of a tuned transformer will be in quadrature with the primary voltage when the frequency of the latter is at resonance, i.e., equal to the frequency of the tuned transformer. When the frequency of the primary voltage deviates from the resonance value, the phase of the secondary voltage will deviate from that of the primary as a linear function of such frequency deviation. This principle is discussed further in Modulation Theory, by Black (1953).

Thus the phase of the voltage across the entire secondary winding of transformer 58 will be 90° behind the phase of the voltage across the primary winding when the incoming IF carrier is unmodulated and hence is at center frequency, f_0 . When the carrier is modulated, its frequency will alternately increase to a frequency $(f_0 + \Delta f)$ and decrease to a frequency $(f_0 - \Delta f)$, causing the phase of the secondary voltage to alternately advance and retard from its normal (carrier unmodulated) 90° relationship. The tertiary untuned winding of transformer 58 is physically connected so that the voltage thereacross, e_t will be substantially 180° out of phase with the primary voltage at all times.

The output voltages from transformer 58, e_s and e_p , are derived from terminals 61 and 64 on either side of the secondary winding. Voltage e_s , which is applied to grid #5, represents the vectorial sum of the tertiary voltage e_t and one half of the secondary winding voltage e_{s1} , measured from the centertap of the secondary winding to point 61. Voltage e_p , which is applied to the plate, represents the vectorial sum of e_t and the other half of the secondary winding voltage, e_{s2} , measured from the centertap of the secondary winding to point 64.

Vector diagram 70 in FIG. 4b, depicts the voltage on transformer 58 when the incoming IF carrier is at frequency f_0 (unmodulated). Vector e_t will be 180° out of phase with the primary voltage (not shown). Vectors e_{s1} and e_{s2} will be respectively 90° ahead of and 90° behind vector e_t at center frequency. The vectorial sum of vectors e_t and e_{s1} will be vector e_s , and vector e_p will be the vectorial sum of e_t and e_{s2} . It should be noted that vectors e_s and e_p are in quadrature and of equal length.

Vector diagram 72 depicts the transformer waveform when the incoming IF carrier modulated and above center frequency, i.e., at a frequency $(f_0 + \Delta f)$. Vectors e_{s1} and e_{s2} will be shifted ahead causing vectors e_s and e_p to become unequal in length, with vector e_p greater than e_s . Vectors e_s and e_p will remain in quadrature as shown if e_{s1} and e_{s2} are equal. Such a relationship may not exist in practice due to inherent asymmetries in the system.

Vector diagram 74 depicts the transformer waveforms when the frequency of the IF carrier is at a frequency below center frequency, i.e., at frequency $(f_0 - \Delta f)$. Here vectors e_s and e_p will be retarded, with vector e_s greater than e_p .

The actual waveforms of the voltages in the circuit of FIG. 4a are depicted in FIG. 4c. It will be noted that voltages e_{g1} and e_t are substantially in phase over the frequency range considered. The alternating voltages e_p and e_s applied to the plate and grid #5, respectively, of tube 46 will be symmetrically phase displaced from voltage e_{g1} at frequency f_0 , with e_s and e_p in quadrature and of equal magnitude. When the frequency of the IF carrier is above or below f_0 , voltages e_p and e_s will be unequal in magnitude and unequally displaced in phase with respect to voltage e_{g1} due to the transformer action aforesubussed.

(3) PHASE COMPARATOR

Grid #5 and the plate of heptode 46 function as a phase comparator which converts the phase-amplitude variations in signals e_s and e_p into a signal representative of the modulation component of signal 40. The rate of the phase-amplitude variations in signals e_s and e_p will be proportional to the frequency of the modulating signal, while the magnitude of the phase-amplitude variations will be proportional to the amplitude of the modulating signal.

More particularly, it can be seen in FIG. 4c that waveforms e_s and e_p are symmetrical about the vertical " z " line from times t_0 to t_4 , when e_{g1} is positive. If the input signal is at frequency f_0 during the approximate interval from t_1 to t_2 , when voltage e_p is greater than e_s , normal plate current will flow as shown by the solid line f_0 in waveform i_p . From the approximate interval from time t_2 to t_3 , secondary emission plate current will flow as also represented by solid line f_0 . Since e_p and e_s are equal and symmetrically phase related to e_{g1} when the IF carrier is at center frequency f_0 , the plate current i_p will average to zero. As shown in vector diagram 72 in FIG. 4b, when the frequency of the IF is above f_0 , i.e., at a frequency $(f_0 + \Delta f)$, e_s and e_p will be advanced in phase position with respect to e_t (and e_{g1}) and magnitude of e_p will increase while e_s will decrease. This will cause the forward part of plate current i_p to predominate over the secondary emission part thereof as shown by the dashed line $f_0 + \Delta f$ in waveform i_p in FIG. 4c. Similarly when the frequency of the IF carrier is below center frequency, i.e., at a frequency $(f_0 - \Delta f)$ the secondary emission part of plate current i_p will predominate as will be evident from an inspection of vector diagram 74 in FIG. 4b and dashed line $f_0 - \Delta f$ in waveform i_p .

When the IF signal is modulated, its frequency will alternately vary above and below center frequency f_0 . The normal and secondary emission components of the

plate current i_p will alternately predominate in conformance to the frequency variations in the IF carrier, and the resulting net component of the plate current will have the same form as the original modulating signal.

5 Deemphasis network 62 restores the signal components in the original modulating signal to their proper relationship in well-understood manner and also removes the signal frequency components of the IF carrier from the plate circuit. The modulating signal, which in most cases will be of audio frequency, will appear at output terminal 44.

10 The output of the limiter-discriminator of FIG. 4a is inherently balanced since direct current will never appear on the plate so long as the frequency of the IF signal applied at input 42 is equal to that to which transformer 58 is tuned.

15 If the frequency of the IF signal should drift, a direct current will appear on the plate. Thus the audio output at point 44 may be used for automatic frequency control (AFC) purposes if desired by first filtering it to remove the audio components and then using the resultant D.C. error signal to control the frequency of the local oscillator.

FIGS. 5a AND b—MODIFICATION OF LIMITER-DISCRIMINATOR

20 It will be apparent that signals e_s and e_p do not have to be at the particular phase relationship shown in FIGS. 4b and c when they are applied to the plate and suppressor of tube 46. For instance the phase relationships shown in FIG. 2b, where e_p and e_{g1} are in phase and e_s lags e_p , may be utilized in conjunction with the circuit of FIG. 4a if transformer 58 is modified as shown in FIG. 5a.

25 In FIG. 5a the ungrounded end of the tertiary winding of transformer 58' is connected to point 64 and the primary-tertiary ratio is made identical to the primary-secondary ratio; otherwise transformer 58' and its connections are identical to transformer 58 and its connections in FIG. 4a. In FIG. 5a voltage e_s is equal to the vectorial sum of the voltage e_t on the tertiary winding, and the voltage e_{sec} on the secondary winding. Voltage e_p is obtained at point 64 and is equal to e_t , the tertiary voltage. Voltage e_p will not vary appreciably 30 in phase as the frequency of the IF carrier changes, but will have substantially the same phase as voltage e_{g1} except at the outer edges of the transformer primary response curve which is beyond the range of interest. Voltage e_s , however, will vary in phase as the carrier frequency changes as is illustrated in FIG. 5b.

35 Vector diagram 70' illustrates the various transformer voltages at center frequency f_0 . Voltage e_{sec} is at 90° from both the primary voltage (not shown) and its inversion, e_t , when the frequency of the IF carrier and the frequency of the tuned transformer secondary are equal. Voltage e_s , the vectorial sum of e_t and e_{sec} , will lead e_t by about 45° . When the frequency of the IF carrier is above f_0 , i.e., at a frequency $(f_0 + \Delta f)$, e_s will advance in phase and decrease in magnitude as shown in vector diagram 72'. When the frequency of the IF carrier is below f_0 , i.e., at a frequency $(f_0 - \Delta f)$, e_s will be retarded in phase and increase in magnitude as shown in vector diagram 74'. The operation of the phase discriminator part of the circuit for these relationships is 40 discussed in conjunction with FIG. 2b. Various other operable phase and/or amplitude relationships between signals e_g , e_p , and e_s (including those of FIGS. 2a and 2c), will occur to those skilled in the art. Concomitant modifications of transformer 58 will be, of course, required, yet these will be similarly obvious to those skilled in the art and hence fall within the scope of the invention.

45 The instant invention is not limited to the specificities of the foregoing description since many modifications thereof which still fall within the true scope of the inventive concept will be apparent to those conversant with

the art. The invention is defined only by the appended claims.

I claim:

1. A phase comparator for a color television receiver for producing a bipolar phase-error indicative signal for controlling a color reference oscillator, comprising:
  - (a) an electron tube having a cathode, at least three grids including a control grid, a second grid, a third grid, and a plate, said third grid being the one closest to said plate,
  - (b) means connecting said cathode to a point at reference potential,
  - (c) means for supplying a positive bias potential to said second grid,
  - (d) means for supplying color reference bursts from the composite color television video signal in said receiver across said control grid and said cathode such that space current flows in said tube to said cathode for intermittent intervals during the duration of each applied burst,
  - (e) means for deriving from the output signal of the color reference oscillator in said color television receiver two dissimilarly phased alternating current signals of the same frequency as said output signal,
  - (f) means for supplying said alternating current signals to said plate and said third grid, respectively, said alternating current signals being phase such that if said output signal and said color reference bursts have like phase, during one part of each said interval when space current flows said third grid will be more positive than said plate, and during another part of each said interval said plate will be more positive than third grid, and
  - (g) alternating current filter means connected to said plate, for passing, a bipolar phase-error indicative output signal from said comparator while suppressing the burst-frequency component of the signal at said plate.
2. The comparator of claim 1 wherein said electron tube includes a fourth grid interposed between said second grid and said control grid, said means of clause (d) is arranged to supply said composite color television video signal, including said color reference bursts, across said control grid and said cathode, and wherein said comparator further includes means for supplying a burst keying signal to said fourth grid so as to enable said tube to conduct only during intervals when said color bursts are present, whereby said phase comparator will also function as a burst keyer.
3. A frequency modulation detector comprising:
  - (a) a vacuum tube having a cathode, at least three grids, and a plate,
  - (b) means connecting said cathode to a point at reference potential,
  - (c) means for impressing a carrier signal which is frequency modulated by an intelligence signal on a first of said grids,
  - (d) means for deriving said carrier signal from a second of said grids in amplified form,
  - (e) means for deriving from said amplified carrier signal two further signals of like frequency as said carrier signal but of dissimilar phase,
  - (f) means for impressing one of said two further signals on a third of said grids and for impressing the other of said two further signals on said plate, said two further signals having phases such that said third

grid will alternately be more positive than said plate at the frequency of said carrier, and

- (g) filter means for deriving said intelligence signal from said plate while suppressing the carrier frequency component of the signal at said plate.
4. A frequency modulation detector comprising:
  - (a) a vacuum tube having at least four grids, a plate, and a cathode connected to reference potential,
  - (b) means for supplying to a first of said grids a carrier signal which is frequency modulated by an intelligence signal,
  - (c) a transformer having a primary winding connected between a second and a third of said grids, said primary winding also being connected to a biasing source, whereby an amplified version of said carrier signal will be supplied across said primary winding,
  - (d) said transformer having a tuned secondary winding inductively coupled to said primary winding for developing oppositely-phased versions of said carrier signal,
  - (e) means for supplying a reference signal having a phase in quadrature with said oppositely-phased versions of said carrier signal,
  - (f) means for adding said reference signal and one of said oppositely-phase signals and for supplying the resultant sum signal to the plate of said vacuum tube, and for adding said reference signal and the other of said oppositely-phase signals and for supplying the resultant sum signal to a fourth of said grids so as to cause normal and secondary emission currents to flow alternately to and from said plate, and
  - (g) filter means for passing said intelligence signal from said plate while suppressing the carrier frequency component of the signal at said plate.
5. An intermediate frequency limiting amplifier and frequency modulation detector comprising, in combination:
  - (a) a heptode having a cathode, plate, and 5 grids, consecutively numbered from cathode to plate,
  - (b) a source of frequency modulated intermediate frequency carrier signal connected between grid #1 and said cathode,
  - (c) means connecting grid #3 to a source of reference potential,
  - (d) a 3-winding transformer having primary, secondary, and tertiary windings, said secondary winding being tuned to said intermediate frequency, said primary winding being connected between grid #2 and grid #4, said tertiary winding being connected between ground and a centertap on said secondary winding, and said secondary winding being connected between grid #5 and said plate, and
  - (e) an output terminal also connected to said plate for deriving a demodulated output signal therefrom.
